UNITED STATES PATENT OFFICE.

JOHN E. DOLDT, OF PORTLAND, MAINE.

AUGER-BIT.

1,244,593.

Specification of Letters Patent. Patented Oct. 30, 1917.

Application filed February 2, 1916. Serial No. 75,656.

To all whom it may concern:

Be it known that I, JOHN E. DOLDT, a citizen of the United States, residing at Portland, in the county of Cumberland and State of Maine, have invented certain new and useful Improvements in Auger-Bits; and I do hereby declare the following to be a full, clear, and exact description of the invention, such as will enable others skilled in the art to which it appertains to make and use the same.

This invention relates to auger bits and more particularly to combined wood boring and routing bits.

The pitch of the spiral at the cutting lips in the usual form of auger bit is about 35° to the axis of the bit. In order to obtain this pitch at the cutting lips, the entire spiral of the bit has a uniform pitch of approximately 35° . While boring with this type of bit, the chips as they are formed at the cutting lips are forced out against the face of the spiral which forms the chip gutter, and since the face of the spiral has a comparatively low pitch, it offers an effective frictional resistance to the movement of the chips along the gutter causing them to pack tightly therein and form a wad, which must be forced along the gutter by the lifting power of the cutting lips and whatever slight conveying action the spiral gutter may have due to the packing of the chips tightly against the inner surface of the whole. This interferes with the boring action of the cutting head, impairing its efficiency and increasing the strain on the bit and the force required to operate it.

The primary object of the present invention is to provide a boring bit which will overcome the objections noted above and which will have an efficient boring action and readily remove the chips.

In accordance with this object one feature of the invention contemplates forming the spiral body portion of the bit of two contiguous sections, the lower cutting section having a comparatively slight pitch to provide an effective cutting angle at the cutting lips, and the upper chip-clearing section having a comparatively steep pitch to form a chip gutter into and through which the chips may move freely longitudinally of the bit, the pitch of the lower section being abruptly merged into the pitch of the upper section. The low pitch of the cutting section extends back from the cutting lips suffi-

ciently far to get an efficient low pitch cutting and lifting wedge, and is then abruptly or rapidly increased to the steep pitch of the chip-clearing section to immediately enlarge the chip gutter. The chips as they are formed by the low pitch cutting lips pass into the comparatively large chip gutter, which is of such a steep pitch that the frictional resistance offered to the travel of the chips is not sufficient to cause them to pack and form a wad. The chips therefore move freely through the large chip gutter without interfering with the efficient and rapid action of the cutting lips or materially increasing the strain on the bit or the force required to operate it. In fact, when boring upwardly, the steep pitch of the chip gutter may allow the chips to fall by gravity away from the cutting lips and out of the hole.

In the illustrated embodiment of the invention the low pitch of the cutting head extends back from the cutting lips a distance about equal to the length of the chip formed, but this length of low pitch is not necessarily fixed, since the low pitch may extend back farther for some classes of work before being abruptly expanded into the steep pitch of the clearing section and still avoid the wadding of chips.

Another object of the invention is to so construct a boring bit that it will be well adapted for routing.

In accordance with this object another feature of the invention contemplates the provision in a boring bit having a spiral body portion with a comparatively steep pitch of a clearance formed behind the leading corners of the spiral edges of the web to produce cutting edges which will give a continuous shear cut when the bit is used for routing.

Still other objects of the invention are to improve certain details of construction of boring bits which will be apparent from an inspection of the accompanying drawings and the following detailed description thereof.

With these objects in view, the invention consists in the improved boring bit herein-after described and set forth in the claims.

The several features of the invention are illustrated in the accompanying drawings, in which Figure 1 is a view in side elevation of my improved boring bit; Fig. 2 is a horizontal section of the spiral body of the bit taken on the line 2-2 of Fig. 1; and

Fig. 3 is an enlarged vertical section of the lead screw taken on the line 3—3 of Fig. 1.

The boring bit shown in the drawings consists of a spiral body portion 10 having a lead screw 12 at its lower end and a shank 14 at its upper end. On the cutting end of the spiral body portion at each side of the lead screw are formed a spur lip 16 and cutting lip 18. The cutting lips are formed 10 at the end of the spiral body portion and have their cutting edges substantially at right-angles to the axis of the bit. The formation of the cutting lips, however, may be varied in getting effective results.

15 To secure a more effective boring bit, the spiral body 10 consists of two sections. The lower section or cutting head 20 starts at the cutting lips and extends back a short distance on the spiral. The pitch or inclination of the section 20 is comparatively slight, so that the cutting lips are given an effective cutting angle. This pitch is preferably slightly greater than the pitch of the thread on the lead screw 12, so that it 25 will tend to force the lead screw into the wood. The upper, or chip-clearing section 22 of the spiral body continues from the cutting section 20 to the shank 14. This section has a comparatively steep inclination or pitch, which provides a large helical groove or chip gutter to receive the chips as they are forced along from the cutting head. The cross-sectional area of the helical groove of the cutting section is much less 35 than the area of the helical groove of the chip-clearing section, so that, as the chips are forced up the spiral by the low pitch wedge of the cutting section, they expand and become freely movable in the chip-clearing section. The large area of the chip gutter in the section 22 allows the chips to loosely move along the gutter, so that the friction of the chips between the face of the gutter and the surface of the hole is 40 very slight. The most effective angle for cutting different kinds of wood can be formed in the cutting section, and the chips when cut are advanced to a spiral with steep pitch, which forms a gutter of sufficient size to take care of the chips no matter how fast they are formed.

45 The steep spiral along the chip-clearing section also permits the formation of chip gutters of adequate area to handle the chips, in which the wall or web between the gutters is much thicker than would be practical in bits having gutters of slight uniform pitch. The thick wall of the spiral increases the strength of the bit so that it will be 50 better adapted to resist the heavy torsional strains which are liable to temporarily distort bits of the usual construction and cause them to bind in a hole or break.

60 To equip the bit for routing, the leading corners of the edges of the spiral body por-

tion are formed into cutting edges 24. As will be seen in Fig. 2, the edges of the spiral body are flat or concave at 26 to form clearance for the cutting edges 24, and the corners 28 opposite the cutting edges are comparatively sharp and extend approximately to the edge of the hole. The edges 24 form continuously acting cutting edges when routing, and since they are formed on a spiral having a comparatively steep pitch, 75 an effective shear cut will be made. While boring a hole, the routing faces 24 will keep the bit centered and form a smooth, true hole. The corners 28 aid the routing faces 24 in holding the bit centered in the hole, 80 and when the bit is reversed in removing it from the hole, the corners 28 prevent chips from becoming wedged between the face of the hole and the edge of the spiral.

When boring with any type of bit which is not properly centered in the chuck or bitstock, the lead screw will hold the cutting end of the bit centered, causing the bit to wobble. This wobbling action places a great strain on the spiral, which acts to crystallize the material so that the bit will soon break. In boring with a bit having a routing edge on its spiral body, the routing edge will gradually cut away the walls of the hole to enlarge it, as the bit wobbles, 95 so that there will be very little strain on the spiral.

100 The lead screw 12 shown in Fig. 3 is provided with a thread or fin 30 which has a special construction for rapid and efficient boring. It will be noted that the upper surface of the fin is flat, while the lower surface is reinforced or bridged to the body of the screw. With this construction, a comparatively thin fin can be formed which will easily force its way into the wood. The reinforcing on the lower edge of the fin further prevents the fin from being stripped off of the screw when the tool is 105 being used for routing.

110 While the invention has been shown and described as embodied in a bit having a lead screw at its cutting end, it will be understood that the broader features of the invention may be embodied with equal advantage in mill bits which do not have lead screws.

115 The shank 14 shown in the drawings is that used in a common type of boring machine, but this shank may be shaped to adapt it to fit any suitable type of chuck or bitstock.

Having thus described my invention, what is claimed as new, is:

120 1. A boring bit comprising a spiral body portion formed in two contiguous sections, the lower cutting section having a slight pitch to provide an effective cutting angle at the cutting lips, and the upper chip-clearing section having a comparatively 125

steep pitch to form a chip gutter into and through which the chips may move freely longitudinally of the bit, the pitch of the lower section being abruptly merged into the pitch of the upper section.

5. A boring bit comprising a spiral body portion formed in two contiguous sections, the lower cutting section having a slight pitch to provide an effective cutting angle 10 at the cutting lips, and the upper chip-clearing section having a comparatively steep pitch to form a chip gutter into and through which the chips may move freely longitudinally of the bit, the pitch of the 15 lower section being abruptly merged into the pitch of the upper section, and the leading corners of the spiral edges being provided with a clearance to form cutting edges for routing.

20. 3. A boring bit comprising a double spiral body portion terminating in oppositely disposed cutting lips, and a lead screw on the body portion between the lips, the edges 25 of the spirals being shaped so that only the corners make point contacts with the face of the hole being bored, the leading corner being a cutting edge for routing.

4. A boring bit comprising a body por-

tion formed in two spiral sections and a shank, the lower section of the body portion 30 consisting of a short cutting head the spiral portion of which has a pitch less than 45° with the axis of the bit, and an upper chip-clearing section, the spiral portion of which has a pitch greater than 45° with the axis 35 of the bit.

5. A boring bit comprising a double spiral body portion formed in two sections, the lower cutting section having a slight pitch 40 extending only a fraction of the distance around the bit, the upper chip clearing section having a steep substantially uniform pitch extending from the end of the cutting section to the shank of the bit.

6. A boring bit comprising a double spiral body portion and a shank, the body portion 45 consisting of a short cutting head having cutting lips and a chip-clearing section extending from the shank to the cutting head, the pitch of the spiral of the cutting head 50 being comparatively slight, and the pitch of the chip-clearing section being comparatively steep, the pitch of the spiral of the cutting head being abruptly merged into the pitch of the chip-clearing section.

JOHN E. DOLDT.
